UNITED STATES PATENT OFFICE

CARL CHRISTOPH EMIL KERSTEN, OF COLUMBUS, GEORGIA

DISTILLING APPARATUS

Application filed June 25, 1929. Serial No. 373,544.

This invention relates to a distilling apparatus and has for its primary object to provide, in a manner as hereinafter set forth, an apparatus for conveniently and expeditiously distilling water and which is adapted to be set up in homes whereby pure water may be readily had for household use.

A further object of the invention is to provide an apparatus of the class aforesaid, which is thoroughly efficient in use, simple in construction, strong, durable, comparatively inexpensive to manufacture and easy to operate.

With the foregoing and other objects in view, the invention consists of the novel construction, combination and arrangement of parts as hereinafter more particularly described, and as illustrated in the accompanying drawings wherein are shown embodiments of the invention, but it is to be understood that the description and drawings are to be taken as illustrative and that the invention is intended to be limited only by the scope of the claims hereunto appended.

In the accompanying drawings wherein like numerals are employed to designate like parts throughout the same:

Figure 1 is a vertical section of a distilling apparatus in accordance with this invention.

Figure 2 is a section taken on line 2-2 of Figure 1.

Figure 3 is a section taken on line 3-3 of Figure 1.

Figure 4 is a section taken on line 4-4 of Figure 1.

Figure 5 is a sectional elevation of a modified form of distilling apparatus in accordance with this invention.

Referring to the drawings in detail, the numeral 1 designates a base upon which is mounted a boiler 2 which is preferably formed with a restricted upper portion 3 and which is open at its top. Disposed beneath the boiler in spaced relation thereto is a heating element 4 which is preferably a Bunsen burner. Disposed between the element 4 and the bottom of the boiler 2 is a heat diffusing element 5 preferably concavo-convex in shape. Seated on the base 1 and enclosing the lower portion of the boiler 2 is a heat

retaining mantle 6, through the upper end of which the boiler 2 extends. Formed on the boiler 2, adjacent the bottom thereof, is a nipple 7 which extends through an opening 8 in the mantle 6 and to the outer end of which is connected a water conducting line 9, such as a hose. The hose 9 leads from a supply tank 10 which is conveniently located with respect to the boiler and from which water is passed through the hose 9 and nipple 7 to the interior of the boiler 2.

The open upper end of the boiler is provided with a cover 11 which is formed with an annular, downturned flange 12 which depends into a trough 13 formed exteriorly of the boiler adjacent the upper end thereof by means of an angular flange 14. Seated on the cover 11 is an insulating member 15, upon which is seated a receptacle 16 which is formed with a vertical, annular partition 17 whereby the interior of the receptacle 16 is divided into an inner compartment 18 and an outer compartment 19. Opening through the cover 11 is a tube 20 which extends upwardly from the cover through the insulating element 15 and receptacle 16.

The partition 17 is of materially greater height than the outer wall 21 of the receptacle 16 and seated on the upper edge of the partition 17 is the bottom 22 of a receptacle 23 which is of materially smaller diameter than the receptacle 16 and which is arranged concentrically with respect thereto. Formed on the receptacle 23 is a downturned annular flange 24 which depends into the outer compartment 19 of the receptacle 16.

Extending through the bottom 22 of the receptacle 23 is a condenser 25 which is of elongated formation and which is formed with a closed upper end and an open lower end. The lower end is arranged in spaced relation to the bottom 26 of the receptacle 16 and depends a substantial distance below the upper end of the tube 20 which is arranged concentrically with respect to the condenser 25. A suitable packing 27 is interposed between the wall of the condenser 25 and the wall of the opening in the bottom 22 of the receptacle 23 through which the condenser 25 extends in order to provide a water-tight

joint between the receptacle 23 and condenser 25. The upper portion of the condenser 25 is substantially star-shaped in cross section and the wall thereof is corrugated as indicated in Figure 2. Partially enclosing the condenser 25 is a cooling tank 28 which is of a construction similar to that of the condenser, as indicated in Figure 2. The tank 28 may be conveniently supported upon a plurality of brackets 29 which are secured to the receptacle 23. Leading into the open upper end of the tank 28 is a supply pipe 30, which is adapted to be connected with any suitable source of water supply for the purpose of conducting water to the interior of the tank 28.

Connecting the outer compartment 19 of the receptacle 16 with the trough 13 is a pipe 31 and connecting the trough 13 with the supply tank 10 is a pipe 32. The supply tank 10 is provided with an overflow pipe 33 by means of which the water in the boiler 2 may be maintained at a constant level during the operation of the apparatus. It is contemplated that the pipe 33 will be positioned at whatever height it is desired to maintain the water level in the boiler.

The pipe 32 opens into the trough 13 adjacent the upper edge thereof in order to maintain a quantity of water in the trough 13 constantly, by means of which the joint between the flange 12 of the cover 11 and the wall of the trough is effectively sealed. The pipe 31 opens into the outer compartment 19 adjacent the upper edge thereof whereby a quantity of water is constantly maintained within the compartment 19 to seal the joint between the flange 24 of the receptacle 23 and the bottom wall of the compartment 19. The opening of the pipe 31 into the compartment 19 is materially lower than the upper edge of the partition 17 whereby the level of the water within the compartment 19 is maintained a material distance below the upper edge of the partition 17. An outlet 34 is provided for the inner compartment 18 and inserted into the outlet 34 is a discharge pipe 35 which is formed with a goose neck 36.

In the operation of my distilling apparatus, water is supplied from the supply tank 10, through the hose 9 and nipple 7 to the boiler 2. The water within the boiler is heated by means of the burner 4 and the steam generated from such heating is passed through the tube 20 into the condenser 25. During the operation of the apparatus, water is continually passed through the pipe 30 into the cooling tank 28 and due to the contact of such water with the wall of the condenser 25, the steam within the latter is condensed and passes through the open lower end of the condenser into the inner compartment 18 of the receptacle 16. From the compartment 18, the pure water may be drawn off through the discharge pipe 35. Owing to the constant

supply of water to the cooling tank 28, the latter continually overflows through an opening 37 and such overflow drops into the receptacle 23, which in turn overflows into the outer compartment 19 of the receptacle 16. From the outer compartment 19, the overflow water is passed through the pipe 31 to the trough 13, thence through the pipe 32 to the supply tank 10.

Owing to the arrangement of the pipes 31 and 32, the overflow water from the cooling tank 28 in its passage to the supply tank 10 constantly maintains a supply of water within the trough 13 and outer compartment 19 as heretofore mentioned. The discharge pipe 35 is rotatable with respect to the outlet 34 whereby the goose neck 36 may be positioned to extend upwardly as shown in Figure 1, or may be positioned otherwise if desired.

In the embodiment shown in Figure 5, the boiler 40 is provided adjacent its open upper end with external threads for engagement with a threaded flange 41 which depends downwardly from the cover 42 for closing the upper end of the boiler. The cover 42 is formed centrally thereof with an upstanding, substantially conical boss 43 which is provided on its upper face with an upstanding, annular flange 44. Spaced from the flange 44, the boss 43 is formed with a shoulder 45, thereby providing in the upper face of the boss 43, a groove 46. From the shoulder 45, the upper face of the boss 43 slopes downwardly and inwardly forming a cup 47. Opening through the cover 42 and extending upwardly through the boss 43 is a tube 48 which projects upwardly from the cup 47, concentrically of the latter. Disposed within the groove 46 is the annular lower end of a condenser 49, the upper portion of which is constructed in the same manner as the condenser 25 described in connection with Figures 1 to 4. The lower end of the condenser 49 bears against the inner face of the flange 44 and is seated on a packing ring 50 disposed within the groove 46 whereby a tight joint is provided between the condenser 49 and boss 43.

Seated on the cover 42 is a pair of insulating elements 51, the inner edges of which conform in contour to the outer surface of the boss 43. Seated on the member 51 is a receptacle 52, the inner annular wall 53 of which fits tightly against the outer face of the flange 44. Supported on brackets 54 extending upwardly from the receptacle 52 is a cooling tank 55, the construction of which is similar to that of the cooling tank 28 described in connection with the form shown in Figures 1 to 4.

In the operation of the apparatus, water overflows from the cooling tank 55 to the receptacle 52, from where it is passed through a pipe 56 to the supply tank 10.

Extending through one of the insulating

members 51 and through the wall of the boss 43 is a discharge pipe 57, the inner end of which opens into the cup 47. The discharge pipe 57 extends downwardly for connection 5 with a receiver 58 for the pure water drawn from the cup 47 and is provided adjacent its lower end with a trap 59. The receiver 58 is provided with a faucet 60 which is disposed above the horizontal plane of the outlet for 10 the pipe 57 in order that the level of the water within the receiver 58 may be maintained above the outlet for the discharge pipe 57. Adjacent the bottom thereof, the receiver 58 is provided with a drain 61 which is located below the horizontal plane of the outlet 15 for the discharge pipe 57.

The formation of the cooling tank as shown in Figure 2 is designed to provide greater area for air contact than would be provided by a 20 cylindrical cooling tank, which more rapidly expels any possible heat which may have been absorbed by the water in cooling tank from the vapor collecting in the condenser. The periphery of the cooling tank is, in the formation indicated, intended to provide a more 25 extended surface for contact with the atmosphere. The periphery of the condenser, in the formation shown, is intended to provide a more extended surface for contact with the 30 water contained in the cooling tank, whereby the heat units are more rapidly conveyed through the water to a greater atmospheric contact by reason of the extensive periphery of the cooling tank in the formation as shown.

35 It is thought that the many advantages of a distilling apparatus in accordance with this invention will be readily apparent, and although the preferred embodiments of the invention are as illustrated and described, it is 40 to be understood that various changes in the details of construction may be resorted to, so long as such changes fall within the scope of the invention as defined in the appended claims.

45 What I claim is:

1. A distilling apparatus comprising, an open top boiler, a removable insulated cover closing the open top of the boiler, a relatively small vapor tube extending through and 50 upwardly from the insulated cover centrally of the latter, a removable open bottom condenser arranged concentrically of the tube with the lower end thereof disposed a material distance above the upper end of the boiler, said tube terminating adjacent the lower end of the condenser, a cooling tank 55 encircling the condenser above said tube and adapted to overflow at its top, a receptacle seated on the insulation of said cover for receiving the overflow from the cooling tank, and means for receiving the condensate formed in the condenser.

2. A distilling apparatus comprising, an open top boiler, a removable cover closing 60 the open top of the boiler, an insulating block

seated on the cover, a relatively small vapor tube extending through and upwardly from the cover and block centrally thereof, a removable open bottom condenser arranged concentrically of the tube with the lower end thereof disposed a material distance above the upper end of the boiler, said tube terminating adjacent the lower end of the condenser, a cooling tank encircling the condenser above said tube and adapted to overflow at its top, a receptacle seated on said insulation block, an annular partition within said receptacle and of greater height than the wall of the latter to divide the receptacle into an inner and an outer compartment, and a second receptacle seated on said partition for receiving the overflow from the cooling tank and adapted to overflow into said outer compartment, said inner compartment being in communication with the open bottom of 75 the condenser to receive the condensate formed therein.

3. A distilling apparatus comprising, an open top boiler, a removable insulated cover for the open top of the boiler, an upwardly and outwardly flaring boss formed centrally of the insulated cover and formed in its upper face with an annular groove, a relatively small vapor tube extending through the cover and boss and projecting above the latter, an 90 open bottom condenser seated in said groove, said boss having its upper face concaved inwardly of said groove to receive the condensate from the condenser, a cooling tank encircling the condenser above said tube and 95 adapted to overflow at its top, and a receptacle seated on the insulation of said cover for receiving the overflow from the cooling tank.

In testimony whereof, I affix my signature 100 hereto.

CARL CHRISTOPH EMIL KERSTEN.
